UNITED STATES PATENT OFFICE.

ERASTUS E. WINKLEY, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHANK-EDGE TRIMMER.

1,372,058.

Specification of Letters Patent. Patented Mar. 22, 1921.

Application filed May 11, 1916. Serial No. 98,781.

To all whom it may concern:

Be it known that I, ERASTUS E. WINKLEY, a citizen of the United States, residing at Lynn, in the county of Essex and State of Massachusetts, have invented certain new and useful Improvements in Shank-Edge Trimmers; and I do hereby declare the following to be a full, clear, and exact description of the invention, such as will enable others skilled in the art to which it appertains to make and use the same.

This invention relates to a machine for operating upon shoes, and it has special reference to machines for finishing sole edges, and particularly for trimming, or partially trimming, the edges of the shank of the out-sole forming part of a partially manufactured shoe.

The shank-edge trimming operation is usually performed on a shoe after the heel has been secured in place, by means of a rotary trimming-cutter, and, in order to bring the trimming-cut up to the breast of the heel, it is necessary to perform subsequently what is known as a "heel-jointing" operation, by which the trimming of the shank-edges is completed either by hand or by a special machine for that purpose. This heel-jointing is necessary both because the ordinary rotary trimming-cutter cannot work up into the angle between the sole and the breast of the heel, and because the shank must be trimmed at its rear extremity, in order to produce a neat finish, with reference to the finished surfaces of the heel and not with reference to the bottom of the crease.

The present inventor has devised a method of making shoes, set forth and claimed in a co-pending divisional application, Serial No. 371,917, filed April 7, 1920, in accordance with which the shank-edges are trimmed before the application of the heel, and in which the heel is also finished before its application, and one object of the present invention is to produce a machine adapted particularly for performing a preliminary shank-edge trimming operation in carrying out the method above referred to. For this purpose the machine is provided with novel means for gaging the depth of the cuts produced in the trimming operation so that this depth, instead of being determined either by the skill of the operator or

by reference to the crease of the shoe, shall be so determined that the trimmed shank-edges shall exactly coincide, at the rear extremity, with the finished surfaces of the heel when the latter is subsequently applied. Since the location of the heel is determined, in the method above referred to, with reference to the original outline of the sole, and preferably by a tongue or narrow extension at the rear extremity of the shank, the machine of the present invention is so constructed as to gage the trimming-cuts, at the rear extremity of the shank, in accordance with the original outline of the sole, and preferably by co-operation of its gaging mechanism with the tongue above referred to.

In another and broader aspect, an object of the present invention is to provide a shoe machine which shall perform its intended operation or function upon each shoe presented thereto in accordance with the particular characteristics of the individual shoe being operated upon. To this end, a feature of the invention resides in the provision of operating means which is prescribed in its action by movable guiding means that is provided with means constructed and arranged to engage each shoe operated upon for adjusting the position of the guiding means in accordance with the individual characteristics thereof.

Other objects of the invention, and the various features of construction by which these objects are attained, will be set forth hereinafter, in connection with the description of the illustrated embodiment of the invention.

In the accompanying drawings Figure 1 is a side-elevation of a machine embodying the present invention; Fig. 2 is a plan-view of a portion of a shoe, showing the character of the work performed by the machine; Fig. 3 is a plan-view of the machine, on a larger scale than Fig. 1; Fig. 4 is a front-elevation of the upper portion of the machine, with a part of the cross-bar broken away; Fig. 5 is a front-elevation of the lower portion of the machine, on a smaller scale than Fig. 4; Fig. 6 is a vertical section on the line 6—6 in Fig. 3, but on a larger scale than the latter figure; Fig. 7 is a section on the line 7—7 in Fig. 1, looking upwardly and on a larger scale than

the latter figure; Fig. 8 is a horizontal section on the line 8—8 in Fig. 5; and Fig. 9 is a vertical section on the line 9—9 in Fig. 4.

The construction and operation of the machine may be best understood in view of the character of the work which it performs. Fig. 2 shows a portion of a lasted shoe, of which the outer sole 11 has been stitched in place and the heel 13 has also been affixed.

10 In this shoe, as hereinbefore described, the sole is provided with a rearward extension or tongue 12 from the rear extremity of the shank-portion of the sole, this tongue being narrower than the shank-portion. The heel 13 is finished before its application, and it is provided with a recess which receives the tongue 12, and whereby the heel is located accurately with respect to the shank of the sole. The edges of the shank-portion have 20 been trimmed previous to the application of the heel, as shown by shading in Fig. 2, the trimming operation involving the removal of the surplus material which is shown by the dotted lines 14 constituting a part of the 25 original outline of the sole.

The principal function of the present machine is to perform the preliminary trimming operation in such a manner that the rear extremities of the trimming-cuts shall 30 leave the shank-portion of the shoe, at its rear extremity, with an outline having an exact relation to the width and location of the tongue 12, so that when the previously finished heel 13 is placed on the sole the 35 finished lateral surfaces of the heel shall be exactly contiguous with the trimmed edges of the shank.

A subsidiary function of the machine is to facilitate the smooth blending of the short 40 trimming-cuts performed by the machine, with the trimming-cuts which may be subsequently performed in the usual manner, in trimming the rest of the shank. This latter trimming operation is guided with reference, not to the original outline of the sole, 45 but rather to the position of other parts of the shoe, particularly the bottom of the crease between the welt and the upper.

The operative instrumentalities of the 50 present machine comprise, as shown particularly in Fig. 7, two rotary trimming-cutters or tools 15, which operate progressively along the sole-edge toward the rear extremities of the shank. The position of the shoe 55 during the trimming operation is accurately and automatically determined with reference to four points of the shoe. Two of these points are the angles between the tongue 12 and the rear extremity of the shank-portion.

60 For this purpose the machine is provided with two gages 16, which may be described as "tongue-gages." The other two points of location are at the bottom of the crease, slightly in advance of the points at which the trimming-cuts are commenced, and these gaging-

points are located by means of two crease-gages 17, having acute ends adapted to enter the creases to the bottoms thereof. In Fig. 7 the sole 11 only of the shoe is shown, for the purpose of illustration, the other parts of 70 the shoe, which are above the section-plane, being omitted, and the bottoms of the crease are indicated by broken lines 18.

When the shoe has been located in the machine by the four gages just described, the 75 paths of operation of the trimming-cutters are determined with reference to the positions of the gages. For this purpose the cutters are rotatably mounted upon laterally-movable slides 19 (Fig. 7), which are 80 provided with guide-rollers 21. Each of these rollers moves along the outer cam-like surface of a cutter-guide or templet in the form of a bar 22. The rear end of each guide is attached, by a pivot 23, to a bracket 85 24 extending forwardly from a slide 25 upon which one of the tongue-gages 16 is also rigidly mounted. The slides 25 move laterally in a guideway 20 on the frame of the machine. Since the pivots 23 are laterally in 90 line with the rear extremity of the shank when the tongue-gages are in engagement with the angle between the tongue and the shank, as shown in Fig. 7, the depth of the cuts produced by the trimming-tools is exactly determined, at the rear extremity of the shank, in accordance with the width of the tongue. Since, also, the sole with the tongue is produced by a dieing-out operation 95 which positively determines the relative 100 widths and positions of the tongue and the shank, it follows that the trimming-cuts have, at the rear extremity of the shank, a definite relation to the original outline of the shank at this point.

It will be observed, also, that the cutter guides or templets 22 are of such length as to extend beyond the heel end of the shank-edge, of the short outsole illustrated in Fig. 7, and that their curvature is such that the 110 rolls 21, in traveling over them, carry the cutters 15 in a path in extension of the curvature of the shank-edge as they leave engagement with the sole. This provides for an exact width of sole at the heel end of 115 the shank equal to the width of the breast of the heel, and a sharp corner on the short outsole to abut the heel breast.

The forward ends of the cutter-guides 22 are connected, by pivots 26, with two slides 120 27, and the crease-gages 17 are also mounted on these slides. For this purpose the crease-gages are provided with shanks 54 which are fastened, by set-screws, in sleeves 55 integral with the slides. The slides move laterally 125 in slide-guides 56 on the frame of the machine.

Since the position of the forward ends of the cutter-guides is determined by reference to the creases of the shoe, it follows that the 130

trimming-cuts, at their forward extremities, are regulated as to depth and position by reference rather to the position of the crease or edge of the last within the shoe, than to 5 the original outline of the shoe-sole, and accordingly the trimming-cuts produced by the present machine may be smoothly blended, at their forward extremities, with trimming-cuts produced in the usual manner 10 and gaged by the crease of the shoe.

Prior to the introduction of the shoe between the gages it is necessary to draw these gages apart, and for this purpose mechanism is employed which is operated by a treadle. 15 To each of the slides 25 a link 28 is attached, by a pivot-screw 29, and the outer ends of the links are pivoted to arms 31 constituting parts of two bell-crank levers which swing about pivot-rods 32 fixed vertically on the frame of the machine. The second arms 33 of the respective bell-crank levers are connected, by short links 34 (Figs. 6 and 9), with the upper and lower ends of a head 35 which slides horizontally 20 on a rod 36. This rod is fixed in brackets 37 on the frame of the machine. A tension-spring 38 (Figs. 7 and 9), connected at its ends with the two lever-arms 31, tends to draw them together so as to move the 30 tongue-gages 16 toward each other, and the arrangement of the levers and the head 35 is such as to cause the movements of the levers and of the tongue-gages to be always equal and in opposite directions, so that when 35 the parts are released from the operation of the treadle 52 (Fig. 1) the spring 38 causes the gages to centralize the tongue as well as to press against the sides of it. At the same time the operator pushes the shoe 40 rearwardly, so as to cause the rear extremity of the shank to engage the tongue-gages.

The head 35 is connected, by a pivot-pin 39, with a link 41 (Fig. 7) which is pivoted to the upper end of a lever 42. This 45 lever is mounted to swing freely on a rod 43 fixed in the frame of the machine. The lever 42 is provided with a lug 44, in position to be engaged by an adjustable screw 45 (Fig. 1) carried by a yoke-shaped lever 50 which also turns upon the rod 43. The lever 46 has an arm 47 which is connected, by a rod 48, with a lever-arm 49. The arm 49 is integral with a sleeve 50 (Fig. 5), which turns on a rod 51 fixed at the bottom 55 of the frame of the machine. A treadle-lever 52 is also integral with the sleeve 50. A spring 53, attached to the treadle-lever, holds it normally in raised position. When the treadle is depressed the lever 46 is 60 swung in a direction to cause the screw 45 to swing the lever 42 forwardly, thus sliding the head 35 forwardly on the rod 36 and causing the tongue-gages to be moved apart. When the parts are in their normal

position the screw 45 is out of engagement 65 with the lug 44, so that the tongue-gages are free to assume their proper operative positions under the influence of the spring 38.

The crease-gages are controlled by mechanism very similar to, and in part common with, that just described. The slides 27 (Fig. 7) are connected, by pivot-pins 58, with arms 57 constituting parts of two bell-crank levers which turn on the rods 32. 70 The other arms 59 of the levers are connected, by links 61, with a head 62 (Fig. 9) which slides on a rod 63 mounted in the brackets 37. This head is connected, by a link 64 (Fig. 7), with a lever 65 arranged 75 alongside the lever 42. The lever 65 cooperates with a second screw 66, carried by the lever 46, so that when the treadle 52 is depressed the crease-gages are moved apart in the same manner as the tongue-gages. 80 The crease-gages are drawn toward each other by the operation of a tension-spring 67 (Figs. 7 and 9) which connects the lever-arms 57.

The trimming-cutters, in addition to rotating, are moved inwardly and outwardly to engage them with and disengage them from the work and to regulate the depth of the cuts produced, and they are also moved in a fore-and-aft direction to cause them 90 to act progressively on the shank and then to return to their original positions. To cause the rotation of the cutters each cutter is mounted on a vertical shaft 68 (Figs. 4 and 8), which turns in upper and lower 95 bearing-sleeve 70 and 80. These sleeves are connected by an integral yoke, as shown in dotted lines in Fig. 4, and each sleeve 70 is integral with the corresponding slide 19.

Between the bearing-sleeves each shaft 100 carries a pulley which is connected, by a belt 78, with a drive-pulley 76.

It is necessary to maintain, during the fore-and-aft movements of the cutters, a constant distance between the cutter-shafts 110 and the drive-pulley 76. Accordingly these parts are connected together by a single fore-and-aft slide. The frame of the machine is provided, at the top, with two longitudinal slide-guides 71 (Figs. 4 and 6), 115 and the slides 19 move in a transverse guide-way 69 which is connected with rearwardly extending slide-bars 72 which move in the slide-guides 71. The bars 72 are connected, at their rear ends, by a yoke 73 and a 120 cross-bar 74, as shown particularly in Figs. 1 and 9. Cheeks 75, which rise from the sides of the slide, provide bearings for the shaft of the drive-pulley 76, and also for the shaft of an idler-pulley 77 which is located in front of the pulley 76 so as to guide the quarter-turn belts 78. The drive-pulley 76 is connected, by a vertical belt 79

(Fig. 1) with a pulley 81 mounted on the power-shaft 82 of the machine. This shaft is driven constantly by connection with any suitable source of power.

5 The movements of the trimming-cutters are performed automatically through a complete cycle, the commencement of the movements being determined by the operator. For this purpose, the slides which 10 control the movements of the cutters are actuated by a cam-mechanism driven through a Horton or one-revolution clutch. The power-shaft 82 is connected, by miter-gears 84 (Fig. 5), with a vertical worm-shaft 86 which is journaled in the frame of the machine. The worm-shaft carries a worm which meshes with a worm-wheel 88 (Fig. 8) rotatable about a cam-shaft 90 which is journaled in the frame.

15 20 The worm-wheel is connected with one member of a Horton clutch 92, of which the other member is fixed to the shaft. The construction of this clutch is not particularly illustrated, as devices of the kind are well known, but it will be understood that the operation of the clutch is controlled, in the usual manner, by means of a stop-member 94 which is provided with a shoulder, as shown in dotted lines in Fig. 1, arranged to 25

30 coöperate with a lug on one end of a detent-lever 96, which is pivoted on the frame of the machine. A spring 98 connected to the lever 96 tends to throw it upwardly so as to engage the shoulder and arrest the movement of the clutch at the completion of each 35 rotation. To permit the clutch to be thrown into operation the detent-lever is connected, by a rod 100, with a treadle-lever 102, which is normally held in its upper position by 40 connection with the same spring 98 by which the detent-lever is controlled. Each time the treadle 102 is depressed and released the cam-shaft 90 performs one complete rotation and then comes to rest.

45 50 The transverse movements of the slides 19, by which the trimming-cutters 15 are brought into and out of engagement with the work, are controlled by a cam 104 (Figs. 5 and 8) on the cam-shaft 90. This cam engages a roller 106 on one arm 108 of a bell-crank lever which turns loosely on a rod 110 fixed on the frame of the machine. The other arm 112 of the bell-crank lever is connected, by a rod 114, with one arm 116 (Fig. 55) of a second bell-crank lever, which turns loosely on a rod 118 which is supported in brackets 119 on the frame of the machine. A second arm 120, integral with the arm 116, is connected, by a link 122, with an arm 124 depending from a sleeve 125. The sleeve turns loosely on a rod 126 which is supported in uprights 127. From the middle of the sleeve 125 an arm 128 projects forwardly, and is provided with a wide end which is 60 65 adapted to engage simultaneously the ends

of two arms 130 (Figs. 3 and 4) projecting from sleeves 132. These sleeves are fixed on rods 134 which are journaled, in parallel positions, in bearings 136 on the frame of the machine. From each sleeve 132 two arms 138 depend, and support a horizontal rod 140. Each of the rods 140 pass through a horizontal opening in the yoke which connects the upper and lower bearings 70 and 80 in which one of the cutter-shafts 68 is supported, as shown particularly in Fig. 4. This arrangement is such that while the rods 140 do not interfere with fore-and-aft movements of the yokes, they cause the yokes, and thus the slides 19 and the trimming-cutters, to move transversely when the arms 138 are rocked. The inward movement of the arms 138 is caused by springs 142, which are coiled around the rods 134, as shown in Fig. 9, and are connected, at their opposite ends, with the bearings 136 and collars on the ends of the rods. The engagement of the cutters with the work is accordingly produced by the resilient action of the springs. 90 The opposite or disengaging movement of the cutters is produced positively, by the action of the cam 104 and the intervening mechanism above described.

The fore-and-aft movements of the cutters, by which they are caused to traverse the sole-edge and also to return to their original positions, is produced by a cam 144 (Figs. 5 and 8) on the cam-shaft 90. This cam engages a roller 146 carried by one arm 148 of a bell-crank lever pivoted on the rod 110, and the other arm 150 of the lever is connected, by a rod 152, with a bell-crank lever 154 (Fig. 7) which is mounted on the rod 118. The other arm 156 (Fig. 9) of the latter bell-crank lever is connected, by a link 158, with a bearing-lug on the cross-bar 74 which forms a part of the fore-and-aft slide by which the slide-guide 69 is supported. This slide is, therefore, moved positively by the action of the cam 144, in proper timed coöperation with the other parts of the mechanism.

To insure an exact registry of the trimming-cutters with the edges of the shank each cutter is provided with a smooth flange 160 (Figs. 7 and 9), which is adapted to enter the crease of the shoe and bear against the grain surface of the welt. This flange is not designed, however, to limit the movement of the trimming-cutter by engagement with the bottom of the crease, since this function is performed, in the present machine, by the guiding-mechanisms heretofore described.

A chute 162 (Figs. 1 and 9) is provided beneath the trimming-cutters to receive the material removed. The chute may be connected, in the usual manner, with an exhauster to carry away the dust.

The operation of the machine, as a whole, is as follows: In the normal position of the parts the trimming-cutters are in their foremost position and are widely separated from each other, and all parts of the machine are at rest, except the power-shaft 82 and the belt-connections by which the trimming-cutters are constantly rotated. The operator holds the lasted shoe, on which a short 10 outsole has been laid, in inverted position and introduces it between the cutters so as to bring the tongue 12 of such an outsole into a position between the tongue-gages 16. While so introducing the work the operator 15 holds the treadle 52 in depressed position, so that the tongue-gages and the cross-gages are held widely apart. The operator then releases the treadle 52, allowing the gages to seat themselves against the work, and at 20 the same time presses the shoe rearwardly to cause the tongue-gages to be engaged by the shoulders at the extremities of the shank of the sole, formed by the tongue 12. The operator then depresses and releases the 25 treadle 102. This causes the clutch to impart one rotation to the cam-shaft 90, and by the action of the cams, as above described, the trimming-cutters are caused, first, to approach and cut into the work to the depth 30 determined by the guides or templets 22, then to move to and past the rear extremities of the shank, so as to trim these extremities to a contour determined by the gages, then to move away from each other and out of 35 engagement with the work, and finally, to return to their original position and come to rest, the cycle of operations of the machine being thus completed. The operator then again depresses the treadle 52, removes the 40 trimmed shoe, and substitutes another.

The invention has been illustrated and described as embodied in a machine arranged to trim only the rear portions of the shank-edges, as this is the function for which the 45 machine is particularly designed, but it will be apparent, that the invention is not limited to embodiment in a machine arranged to operate in this restricted manner.

In the embodiment of the invention illustrated in the drawings the features of the 50 invention are disclosed in a machine having tools for shaping a portion of the sole edge, but those skilled in the art will readily recognize, and it is particularly pointed out, that 55 as to certain features herein described the scope of the invention is not circumscribed by the illustrated embodiment, as such features are applicable and useful in machines for performing other sole edge preparing 60 and finishing operations, as well as general operations of various characters. Furthermore, it will be apparent that the invention is not limited to the conjoint use of all its features and may be embodied in various

other forms within the nature of the invention as it is defined in the following claims. 65

I claim—

1. A shank-edge trimming machine having, in combination, a trimming-tool for operating on the shank-edge of the sole of a 70 shoe; and means for automatically determining the depth of the cut produced by the tool, at the rear extremity of the shank, with a fixed relation to the outline of the sole.

2. A shank-edge trimming machine, for 75 operating on a shoe-sole provided, at its rear-end, with a tongue continuous with but narrower than the shank of the sole, said machine having, in combination, trimming-tools for operating on the shank-edges of the 80 sole; and means operative automatically, by engagement with the lateral edges of said tongue, for determining the depth of the cuts produced by the trimming-tools at the rear extremity of the shank. 85

3. A shank-edge trimming machine having, in combination, a tool for trimming the shank-edge of the sole of a shoe, and means for automatically determining the depth of the trimming-cut, at the rear extremity of 90 the shank, with a fixed relation to the outline of the sole, and, at points in advance of said rear extremity, with relation to other characteristics of the shoe.

4. A shank-edge trimming machine, having, in combination, tools for trimming the shank-edges of the sole of a shoe; and means for guiding said tools to produce trimming-cuts extending from points, at the rear extremity of the shank, determined in accordance with the outline of the sole, to points, in advance of said rear extremity, determined with relation to the crease of the shoe. 95

5. A sole-edge trimming machine having, 105 in combination, trimming-means comprising a cutter; means for holding a shoe with the cutter in engagement with the sole-edge; and mechanism adjustable to a portion of the outline of the sole for guiding one of 110 said means in a movement, with respect to the other said means, whereby the cutter is caused to have a progressive operation along the sole-edge. 110

6. A sole-edge trimming machine having, 115 in combination, trimming-means comprising a cutter; means for holding a shoe with the cutter in engagement with the sole-edge, and with the axis of the cutter approximately normal to the plane of the sole; and mechanism automatically adjustable to the 120 shoe for guiding said cutter in a movement, with respect to the holding means, whereby the cutter is caused to have a progressive operation along the sole-edge. 125

7. A sole-edge trimming machine having, in combination, trimming-means comprising a cutter; means for normally holding

a shoe adjacent to the cutter with its sole-edge out of engagement therewith; and mechanism for first causing a movement, of one of said means with respect to the other, 5 whereby the cutter is caused to laterally approach and engage the sole-edge as aforesaid, and for thereafter causing a movement, of one of said means with respect to the other, whereby the cutter is caused to have a progressive action along the sole-edge.

8. A sole-edge trimming machine having, in combination, trimming-means comprising a plurality of cutters; means for supporting 15 a shoe in coöperative relation with the trimming-cutters, and mechanism automatically adjustable to each shoe operated upon for moving one of said means relatively to the other to produce a progressive 20 engagement of the cutters with the edges of the sole.

9. A sole-edge trimming machine having, in combination, trimming-means comprising a plurality of cutters; means for supporting 25 a shoe in coöperative relation with the trimming-cutters, mechanism for moving one of said means relatively to the other to produce a progressive engagement of the cutters with the edges of the sole, and means 30 coöperating with the shoe for independently determining the depths of the respective trimming-cuts.

10. A sole-edge trimming machine having, in combination, trimming-means comprising 35 a pair of cutters; means for normally supporting a shoe between the trimming-cutters; and mechanism operating automatically to first move the trimming-cutters toward each other and into engagement with 40 opposite edges of the sole, and then produce a movement of one of said means relative to the other, whereby the cutters are caused to traverse the sole-edges.

11. A machine for operating on shoes, 45 having, in combination, a tool for operating on the sole at its edge, means for moving said tool along the sole edge while in engagement therewith, and means for guiding said tool at one portion of the edge in accordance with the outline of the crease of 50 the shoe and at another portion in accordance with the outline of the sole.

12. A machine for operating on shoes, having, in combination, a tool for operating 55 on the sole at its edge, means for moving said tool along the sole edge at the shank portion thereof while in engagement therewith, and means for guiding said tool at the heel end of the shank in accordance 60 with the outline of the sole and at the ball end of the shank in accordance with the outline of the crease of the shoe.

13. A machine for operating on shoes, having, in combination, means comprising 65 a tool for operating on the sole edge, means

for holding the shoe with the tool in engagement with said sole edge, and means adjustable to a portion of the outline of the sole for guiding one of said means in a movement, with respect to the other of 70 said means, whereby the tool is caused to have a progressive operation along the sole edge.

14. A machine for operating on shoes, having, in combination, a tool for operating 75 on the sole edge, a gage arranged to co-operate with the edge of a portion of the sole, and means for guiding the tool in a path of operation predetermined by the position assumed by the gage.

15. A shank edge finishing machine, having, in combination, a finishing tool, means for moving the tool and shoe relatively to produce a progressive action of the tool along the shank, and means for determining 85 the path of movement of the tool by gaging from the outline of the sole at the heel end of the shank and from other characteristics of the shoe at the ball end of the shank.

16. A shank-edge finishing machine for short out-soles, having, in combination, a finishing tool, means for moving the tool along the shank-edge, and tool guiding means permitting the tool to travel beyond 95 the heel end of the shank in a path in extension of the curvature of the shank-edge at this point.

17. A shank-edge finishing machine for short out-soles, having, in combination, a 100 finishing tool, a tool guide having an outline corresponding to the finished shank-edge and longer than the shank-edge, and means for moving the tool along the shank-edge.

18. A sole edge trimming machine, having, in combination, a trimming-tool, and means, for determining the depth of the cut produced by the tool, arranged to engage a part of the sole other than that upon which the 110 tool is operating, simultaneously with such operation, and to gage the cut with relation to such other part of the sole.

19. A machine for operating upon shoes having, in combination, a movable guiding 115 templet, means arranged to engage each shoe operated upon for adjusting the position of the templet, and means guided by said templet for operating upon the shoe.

20. A machine for operating upon shoes 120 having, in combination, a plurality of guiding templets adjustable to each shoe operated upon, and a plurality of tools guided by the respective templets for operating upon the shoe.

21. A machine for operating upon shoes having, in combination, movable templet guiding means, means arranged to engage each shoe operated upon for adjusting the position of said templet guiding means, operat- 130

ing means, and means for effecting relative movements of the shoe and the operating means in accordance with said adjustable templet guiding means whereby said shoe 5 is operated upon.

22. A machine for operating upon the edges of shoe soles having, in combination, movable templet guiding means, means arranged to engage each shoe operated upon to adjust 10 the templet guiding means to conform to each shoe, and means prescribed in movements by said templet guiding means for progressively operating upon the sole edges.

23. A machine for operating upon shoe 15 soles having, in combination, operating means, means for progressively actuating said operating means along the shoe sole, and means comprising a movable templet, and means arranged to engage each shoe operated 20 upon for adjusting the position of the templet for determining the path of movement of said operating means.

24. A machine for trimming the sole edges of lasted shoes having, in combination, 25 trimming means comprising a plurality of cutters, means for concurrently actuating said cutters through their trimming movements, and templet mechanism adjustable to different portions of each shoe operated 30 upon for prescribing the path of movement

of said cutters during their trimming operation.

25. A machine for operating on shoes having, in combination, a plurality of tools for operating upon the edge of the sole, means 35 for concurrently moving said tools along the sole edge while in engagement therewith, and means for guiding said tools at certain portions of the edge in accordance with the outline of the crease of the shoe and at other 40 portions thereof in accordance with the outline of the sole.

26. A finishing machine for operating upon shoes having, in combination, finishing means, means for moving said finishing 45 means and shoe relatively to produce progressive action of the finishing means along the edge of the shoe sole, and guiding means positioned by engagement with each shoe operated upon prior to the finishing operation 50 for determining the path of movement of the finishing means.

27. A machine for operating upon shoes having, in combination, a movable guiding templet, means automatically adjustable to 55 each shoe operated upon for positioning said templet, and means guided by said templet for operating upon the shoe.

ERASTUS E. WINKLEY.
